COMB AND BRUSH COMBINATION

Filed March 20, 1950

UNITED STATES PATENT OFFICE

2,531,239

COMB AND BRUSH COMBINATION

Frank L. Twitty, Bronxville, N. Y.

Application March 20, 1950, Serial No. 150,598

5 Claims. (Cl. 132—85)

1

The invention herein disclosed relates to comb and brush combinations and special objects of the invention are to so combine the comb and brush forming elements that they may be readily separated and put together and be securely held when they are in the assembled relation.

Further special objects of the invention are to provide a simple, inexpensive form of construction consisting of but few parts and which will be of neat, compact design and free of objectionable projections.

Other desirable objects and the novel features through which the purposes of the invention are attained are set forth or will appear in the course of the following specification.

The drawing accompanying and forming part of the specification shows by way of illustration a practical and at present, preferred embodiment of the invention. Structure, however, may be modified and changed as regards this illustration, all within the true intent and broad scope of the invention as hereinafter defined and claimed.

Figure 1 in the drawing is a side elevation of one of the new brush and comb combinations.

Figure 2 is a top plan view of the same.

Figure 3 is a broken part sectional side elevation similar to Figure 1 but showing the toggle lever lifted to release the brush elements at the opposite sides of the comb.

Figure 4 is an end view of the structure.

Figure 5 is a broken sectional detail as on substantially the plane of line 5—5 of Figure 1.

The construction shown comprises a comb having straight back and handle portions 7, 8 and brushes 9 on spiral wire cores 10 at opposite sides of the comb.

The brushes are held in this relation by having the core portions 10 supported at one end in fixed sockets 11 offset from opposite sides at one end of the comb and at the opposite end in companion sockets 12 carried by a toggle lever 13 pivoted at 14 at the junction of the back and handle portions of the comb.

The fixed sockets 11 are shown as provided by angle brackets having base portions 15 riveted at 16 to the opposite sides of the back and having indentations 17 entered in depressions 18 in the back to lock these brackets against turning on the comb.

The toggle lever is shown provided as a single piece of sheet material folded at the middle to form a handle and stop overlying the back of the comb handle 8 and parallel side portions 20

2

straddling the handle and terminating in lateral offsets 21 carrying the sockets 12.

The pivot 14 for the toggle lever is shown as a tubular rivet extending through the straddling side portions 20 of the lever and the intermediate handle portion of the comb and this pivot is so located that the lever will carry the brush holding sockets 12 through dead center position in swinging from the fully closed relation shown in Figure 1 with the stop portion 19 engaging the back of the handle to the open brush releasing position shown in Figure 3, where the forward edge 22 of the stop portion engages the back of the handle to limit the opening movement.

15 The toggle lever thus has a limited travel in both directions, assuring in the Figure 1 position that it will not turn further in the right handed direction to release the brush elements, and that it will stand in the open Figure 3 position to assist in locating the ends of the brush cores in the fixed and movable sockets 11 and 12 respectively.

Both the angle brackets for the fixed sockets and the toggle lever itself may be of springy sheet metal or material and the brush cores be of a length to apply end tension on these parts so that the toggle lever will be held in the past dead center position, Figure 1 under a certain amount of spring tension.

20 Additionally, if desired, other spring detent means may be provided such as the indentations 23 in the sides of the toggle lever positioned to snap into recesses 24 in the sides of the comb handle.

35 While shown as separately applied angle brackets, it is contemplated that the fixed sockets 11 may be made as integral portions of the comb structure or be otherwise provided on the comb.

40 The whole combination is of simple, rugged construction, consists of but few parts and is free of objectionable protuberances that might catch in the hair.

45 The brushes can be quickly and immediately removed by simply rocking the toggle lever past dead center from the Figure 1 to the Figure 3 position and it is equally easy to apply the brushes by engaging the ends of the cores in the opposed sockets 11 and 12 and then rocking the lever down into the Figure 1 position. This enables the parts to be separated for cleaning or for substitution of different kinds of brushes or for the use of a single instead of two brushes and this construction, with the easy separation of parts, enables brushes or comb to be used sep-

arately, for massage or other purposes and to be reconnected when through with such separate use.

The construction is neat and attractive in appearance and by reason of its simple design and construction, can be produced at relatively low cost.

What is claimed is:

1. The herein disclosed comb and brush combination comprising a comb having back and teeth portions, brackets projecting from opposite sides of said back portion and having sockets offset from said opposite sides, a toggle lever pivoted on said back portion at a distance from said brackets and having sockets opposed to and in line with the sockets in the brackets when said lever is rocked into position past dead center, brushes having cores of a length to be held in opposed sockets of the brackets and lever when the lever is in said past dead center position and to be released from said sockets when the lever is rocked in the opposite direction and means for limiting movement of the lever to said past dead center position, said lever being forked to straddle the back portion and said means for limiting movement of the lever being that portion of the lever straddling the back of the comb.

2. The herein disclosed comb and brush combination comprising a comb having back and teeth portions, brackets projecting from opposite sides of said back portion and having sockets offset from said opposite sides, a toggle lever pivoted on said back portion at a distance from said brackets and having sockets opposed to and in line with the sockets in the brackets when said lever is rocked into position past dead center, brushes having cores of a length to be held in opposed sockets of the brackets and lever when the lever is in said past dead center position and to be released from said sockets when the lever is rocked in the opposite direction, means for limiting movement of the lever to said past dead center position, said lever being forked to straddle the back portion and said means for limiting movement of the lever being that portion of the lever straddling the back of the comb and companion detent shoulders on said lever and comb back for releasably retaining the lever in said past dead center position.

3. The herein disclosed comb and brush combination comprising a comb having back and teeth portions, brackets projecting from opposite sides of said back portion and having sockets offset from said opposite sides, a toggle lever pivoted on said back portion at a distance from said brackets and having sockets opposed to and

in line with the sockets in the brackets when said lever is rocked into position past dead center, brushes having cores of a length to be held in opposed sockets of the brackets and lever when the lever is in said past dead center position and to be released from said sockets when the lever is rocked in the opposite direction and means for limiting movement of the lever to said past dead center position, said lever being of spring sheet material doubled over the back portion of the comb and having indented portions for yieldingly gripping the opposite sides of said back portion.

4. A comb having a fixed supporting socket, a toggle lever pivoted on said comb at a distance from said fixed socket and having a socket to align therewith when said lever is rocked to a past dead center position, a brush having a core of a length to be held in said sockets when said lever is in said past dead center position and to be released therefrom when the lever is rocked in the opposite direction, said lever being of sheet material folded to straddle over the back of the comb and to engage the back of the comb to limit movement of the lever to said past dead center position.

5. A comb having a fixed supporting socket, a toggle lever pivoted on said comb at a distance from said fixed socket and having a socket to align therewith when said lever is rocked to a past dead center position, a brush having a core of a length to be held in said sockets when said lever is in said past dead center position and to be released therefrom when the lever is rocked in the opposite direction, said lever being of sheet material folded to straddle over the back of the comb and to engage the back of the comb to limit movement of the lever to said past dead center position and said straddling portion of the lever having an edge at the end nearest the pivot engageable with the back of the comb to limit movement of the lever in the opposite direction.
